PUMP

Howard M. Geyer and Howard Carson, Dayton,
Ohio, assignors to General Motors Corporation,
Detroit, Mich., a corporation of Delaware

Application December 5, 1944, Serial No. 566,681

10 Claims. (Cl. 103—173)

1

This invention relates to high pressure pumps for use with hydraulically operated apparatus such as, for example, the servo-motor which adjusts the pitch of airplane propeller blades.

An object of the invention is to provide a durable pump which, in proportion to its size, is capable of delivering liquid under relatively high pressure and which can be produced at relatively low cost. Therefore it is the aim of the invention to provide a construction which involves the use of a relatively small number of parts. To accomplish this, the pump comprises a housing providing a plurality of cylinders each receiving a pair of oppositely reciprocating pistons and a drive shaft which provides the movable valve members of the pump and which carries the means for imparting positively to the piston reciprocal motion in both directions.

Further objects and advantages of the present invention will be apparent from the following description, reference being had to the accompanying drawings, wherein a preferred embodiment of the present invention is clearly shown.

In the drawings:

Fig. 1 is a fragmentary longitudinal section view of a portion of an airplane propeller pitch-regulator showing a side view of a pump embodying the invention.

Fig. 2 is a sectional view on line 2—2 of Fig. 4.

Fig. 3 is a sectional view on line 3—3 of Fig. 2.

Fig. 4 is a sectional view on line 4—4 of Figs. 1 and 2.

Fig. 5 is a perspective view of a fragment of the longitudinal section of the pump showing details of construction on a larger scale than the preceding figures.

Fig. 6 is a view of one side of the pump shaft.

Fig. 7 is a sectional view on line 7—7 of Fig. 6.

Fig. 8 is a view of that side of the pump shaft diametrically opposite to the side shown in Fig. 6 and a sectional view of a bearing washer assembled with the shaft.

Fig. 9 is a side view of a wobble plate to be assembled with the shaft shown in Fig. 8 and a sectional view of a bearing washer assembled therewith.

Fig. 10 is a side view of a clamp washer to be assembled with the pump shaft.

Fig. 11 is a diagrammatic view showing the relation between the bearing washer, shown in section in Fig. 8, and the pump pistons associated therewith.

Fig. 12 is a view in the direction of arrow 12 of Fig. 11 all but one of the pistons being omitted for sake of clearness.

2

Fig. 13 is a view similar to Fig. 11 showing the relation between the bearing washer, shown in section in Fig. 9 and its associated piston.

Fig. 14 is a view in the direction of arrow 14 of Fig. 13, all but one of the pistons being omitted for sake of clearness.

Fig. 15 is a chart showing the relation of pistons positions and valve positions.

In Fig. 1, there is shown an adapter of tubular formation comprising parts 10, 11 and 12 which are secured together by screws, such as screw 13; and the part 12 is attached to a portion 14 of the engine frame indicated in dot-dash lines. This adapter surrounds the engine driven shaft (not shown) which carries the propeller hub. To the propeller hub there is secured a housing plate 15 carrying a cover 16. The members 15 and 16, which are of annular formation, together with the tubular adapter part 10 and annular sealing members 17 and 18 provide an annular chamber for enclosing parts of an hydraulic system for controlling the application of hydraulic pressure to servo-motors which rotate the propeller blades about their root axes in order to govern the speed of the engine. One of the parts of the hydraulic system is the pump 20 which will now be described.

Pump 20 comprises a housing 21 having a cylindrical part 22 received by the cylindrical wall 30 23 defining a recess 24 of housing 15 which encloses the pump. From the part 22, there extends a flange 25 having holes 26 for receiving screws by which the pump housing 21 is secured to the plate 15. When the housing 21 is secured in position, its outlet passage 27 is placed in communication with a passage 27a of plate 15 leading to a manifold having parts 28, 29 and 30 for conducting pressure fluid to other parts of the hydraulic system. A washer 31 seals the joint between the passages 27 and 27a. For details of the systems, reference is made to Blanchard and MacNeil Patent No. 2,307,102, filed January 15, 1943.

Referring to Fig. 2, passages 33 and 34 connect passage 27 with the central bore 35 in the housing 21 which provides a bearing for the pump drive shaft 40 having an inlet passage 41 which will be submerged with the hydraulic fluid or oil contained within the housing parts 15 and 16 when rotating, the annular rotating level being indicated approximately by line x—x in Fig. 1. Oblique passage 42 connects inlet 41 with a recess 43 provided by the shaft 40 as shown in Figs. 2, 3, and 8. This recess 43 is wide enough to reach to two and sometimes thru ports 44, each leading to a displacement chamber within a pump cy-

cylinder 45, there being five pump cylinders in the disclosed embodiment. Each port 44 is provided by drilling the holes 46 and 47 which are plugged.

Each cylinder 45 receives a pair of oppositely reciprocating pistons. The pistons to the left of section line 3—3 of Fig. 2 are marked I to V, and those to the right are marked I' to V'. During practically all of the travel of a pair of pistons away from each other the port 43 is so disposed as to connect the pump inlet with the cylinder enclosing that pair of pistons. During practically all of the travel of a pair of pistons toward each other the port 44 of the cylinder enclosing that pair of pistons is connected with the pump outlet 27 by a recess 50 (Figs. 2, 3 and 6) a channel 51 and an annular groove 52 always connected with passage 34. The channel 53 connects the recess 50 with an annular groove 54 for supplying lubrication to the shaft bearing more remote from the recess 50.

The valve recesses 43 and 50 are diametrically opposite and are separated by blocking areas A and B each of a width slightly exceeding the width of each port 43 as best shown in Fig. 15. In that figure line M—M represents a plane passing through the center of each cylinder 45. Line l—m—n, which represents the relation of movement of pistons I to V to rotation of the pump shaft, passes through the centers of short horizontal lines marked I to V which represent the inner ends of these pistons. Line l'—m'—n' which represents the relation of movement of pistons I' to V' to the rotation of the pump shaft, passes through the center of short horizontal lines marked I' to V' which represent the inner ends of these pistons. Lines l—m—n and l'—m'—n' are sine curves denoting that the motion of the pistons is simple harmonic motion in relation to shaft rotation. The rate of piston travel relation to shaft rotation near the beginning and the end of stroke is relatively small.

When pistons I and I' are beginning to separate, the port 44_I of their cylinder 45 is blocked by the shaft surface B between recesses 50 and 43. At that instant the pistons II, II', and III, and III', which are separating, are in the positions shown in Fig. 15 and their respective cylinder ports 44_{II} and 44_{III} are connected by recess 43 with the pump inlet. At the same instant, the pistons IV, IV', and V, V', which are approaching, are in the positions shown and their respective cylinder ports 44_{IV} and 44_V are connected with the pump outlet by recess 50. When any pair of pistons, such as I and II, arrive at the inner ends of their strokes, their cylinder port is blocked by shaft surface B; and when at the outer ends of their strokes, their cylinder port is blocked by shaft surface A. During their brief intervals when a cylinder port is blocked, the rate of piston travel is low; therefore the amount of hydraulic braking is inconsequential.

The pistons I to V are caused to reciprocate by rotation of a wobble-plate 60 (Figs. 1, 2, 6 and 8) integral with shaft 40. Motion of plate 60 is imparted to the inclined heads 70 of the pistons through an interposed wobble-ring 61 of bearing bronze journaled on an eccentric boss 62 which is located next to a groove 63 between the boss 62 and a flange 64 having a wobble surface 65 for engaging the inner side plane surfaces of the piston heads 70 which are received by the groove 63. The center of the shaft 40 is indicated at 40c and the center of the boss 62 is indicated at 62c of Fig. 11. Each head 70 of a piston I to V is connected with the ring 61 by a crank pin 71

which extends at right angles to the plane upper face of the piston head 70 and is received by a hole in the ring. As the wobble-plate 60 rotates, the center of wobble-ring 61 oscillates in the path denoted by circle 61p in Fig. 11, and causes each of the five pistons to rotate as denoted by the circles 71p. This connection between the wobble-ring and the piston heads accomplishes two things, namely: (1) The outer surface of each piston head 70 is caused to be in coincidence with the plane of the adjacent surface of the ring 61 so that the force exerted by the ring to move the pistons inwardly is distributed over the engaging surfaces of the ring and piston head. There can be no cocking of a piston head surface relative to the ring surface, and no point or line contact. A surface contact is insured. (2) Since each piston must rotate as it reciprocates, there is no straight line scoring of the engaging surface of the piston and cylinder. The pistons are positively moved in both directions, namely: they are moved in by the wobble-plate 60 and out by the flange 64 whose surface 65 operates as a wobble-plate.

The foregoing applies to the operation of pistons I' to V' which are operated by the unit 80 (Figs. 9, 13 and 14) having parts corresponding in function to the similarly numbered parts of Figs. 8, 11 and 12, the reference numbers of the parts of Figs. 9, 13 and 14 having a prime affixed. The unit 80 is attached by a key 81 (Fig. 2) to the shaft 40. A washer 82 is located next to wobble-plate 60; and, by means of a nut the unit 80 is forced against a shoulder 84 of shaft 40. This nut is the hub of 91 of a gear 90 which meshes with a gear 92 integral with part 10 (Fig. 1) having its axis substantially in coincidence with the axis of the engine shaft. After screwing on the gear hub 91, a hole is drilled through the hub and shaft and a pin 93 is driven through. As the housing 15, 16 rotates around the axis of the engine shaft, part 10 being fixed, the gear 90 rotates at relatively high speed.

It will be noted by referring to Figs. 8 and 9 that the eccentric bosses 62 and 62' are diametrically opposite. Therefore when wobble-ring 61 is up (Fig. 1), the wobble-ring 61' is down. The purpose of this arrangement is to obtain dynamic balancing of the rotating parts with respect to the axis of shaft 40. Therefore the crank pins 71 (Fig. 12) extend from the upper portions of the inclined surfaces of the heads 70 of pistons I to V, and the crank pins 71' (Fig. 14) extend from the lower portions of the inclined surfaces of the heads 70' of pistons I' to V'.

The motions positively imparted through the wobble-members by the shaft to the pistons in both directions are simple harmonic motions.

While the embodiment of the present invention as herein disclosed, constitutes a preferred form, it is to be understood that other forms might be adopted, all coming within the scope of the claims which follow.

What is claimed is as follows:

1. A fluid pump comprising a housing having a central bore and a plurality of cylindrical displacement chambers parallel to the bore and equally spaced in a circular row concentric with the bore, pistons reciprocable in the displacement chambers, displacement chamber inlet and outlet ports each connecting a displacement chamber with the bore, a rotatable shaft journaled in the bore and having inlet and outlet recesses rotatable past the ports and separated by valve lands provided by shaft surfaces closely fitting

the bore, a fluid inlet duct connected with the inlet recess of the shaft, a single fluid outlet duct for all of the displacement chambers connected with the outlet recess of the shaft, and means operated by the shaft for imparting reciprocating motion to the pistons and so related to the shaft recesses that, during an intake stroke of a piston, its chamber port is connected with the inlet recess of the shaft and, during the discharge stroke of a piston, its chamber port is connected with the outlet recess of the shaft, each chamber port being completely blocked by a valve land at the end of a stroke of its associated piston.

2. A fluid pump according to claim 1 further characterized by the fact that the valve lands are slightly wider than the ports and by the fact that the means which transmits motion from the shaft to the pistons operates to impart to the pistons a relatively small amount of movement near the ends of their strokes whereby hydraulic braking of the pump, when a chamber port is blocked by a valve land, is minimized.

3. A fluid pump according to claim 1 further characterized by the fact that the inlet duct is provided by a passage in the shaft for connecting a supply of fluid with the inlet recess of the shaft within the bore, and by the fact the outlet duct from the outlet recess of the shaft is provided by a longitudinal groove in the shaft and by an annular groove in the shaft longitudinally displaced from the chamber ports and connected with the longitudinal groove and by a passage in the housing connected with the annular groove.

4. A fluid pump comprising a housing having a central bore and a plurality of cylindrical displacement chambers parallel to the bore and equally spaced in a circular row concentric with the bore, pistons reciprocable in the displacement chambers, ports each connecting a displacement chamber with the bore, fluid inlet and outlet ducts, a rotatable shaft journalled in the bore and having valve means for connecting chamber ports with the inlet duct during intake strokes of their associated pistons and for connecting chamber ports with the outlet duct during discharge strokes of their associated pistons and means operated by the shaft for imparting reciprocatory movement to the pistons and for imparting rotary motion during reciprocation whereby longitudinal scoring of the contacting surfaces of pistons and chambers is avoided.

5. A fluid pump comprising a housing having a central bore and a plurality of cylindrical displacement chambers parallel to the bore and equally spaced in a circular row concentric with the bore, pistons reciprocable in the displacement chambers, ports each connecting a displacement chamber with the bore, fluid inlet and outlet ducts, a rotatable shaft journalled in the bore and having valve means for connecting chamber ports with the inlet duct during intake strokes of their associated pistons and for connecting chamber ports with the outlet duct during discharge strokes of their associated pistons, and means operated by the shaft for imparting reciprocatory movement to the pistons positively in both directions and for imparting continuous rotary movement to the pistons during reciprocation in both directions whereby longitudinal scoring of the contacting surfaces of pistons and chambers is avoided.

6. A fluid pump comprising a housing having a central bore and a plurality of cylindrical displacement chambers parallel to the bore and equally spaced in a circular row concentric with

the bore, pistons reciprocable in the displacement chambers, ports each connecting a displacement chamber with the bore, fluid inlet and outlet ducts, a rotatable shaft journalled in the bore and having valve means for connecting chamber ports with the inlet duct during intake strokes of their associated pistons and for connecting chamber ports with the outlet duct during discharge strokes of their associated pistons, and means operated by the shaft for causing each piston to complete a cycle of reciprocations and simultaneously to rotate one revolution for a revolution of the shaft whereby longitudinal scoring of the contacting surfaces of the pistons and chambers is avoided.

7. A fluid pump comprising a housing having a central bore and a plurality of cylindrical displacement chambers parallel to the bore and equally spaced in a circular row concentric with the bore, pistons reciprocable in the displacement chambers, ports each connecting a displacement chamber with the bore, fluid inlet and outlet ducts, a rotatable shaft journalled in the bore and having valve means for connecting chamber ports with the inlet duct during intake strokes of their associated pistons and for connecting chamber ports with the outlet duct during discharge strokes of their associated pistons, piston heads having inner and outer parallel plane surfaces oblique to the axis of the piston, a flange on the shaft having an oblique plane surface for engaging the inner surfaces of the piston heads, a wobble-washer oblique to the shaft for engaging the outer surfaces of the piston heads, a circular boss provided by the shaft eccentrically thereof upon which the wobble-washer is journalled a wobble-plate provided by the shaft obliquely thereof for engaging the wobble-washer, and crank connections between the wobble-washer and the piston heads whereby, as the wobble-washer is caused to wobble and move eccentrically relative to the shaft, the pistons are caused to rotate in order to maintain their head-inner-surfaces in the plane of the oblique surface of said shaft-flange and in order to maintain their head-outer surfaces in the plane of the engaging surface of the wobble-washer, and whereby rotation of the pistons avoids scoring of the contacting surfaces of the pistons and chambers.

8. A pump according to claim 7 further characterized by the fact that the crank connection between the wobble-washer and the piston heads are provided by crank-pins which are fixed to the heads and extending at right angles to the outer surfaces of the heads and the wobble-washer is provided with holes for receiving the crank-pins.

9. A fluid pump comprising a housing having a central bore therethrough and a plurality of bores therethrough to provide cylindrical displacement chambers parallel to the bore and equally spaced in a circular row concentric with the central bore, two pistons oppositely reciprocable in each chamber, ports each for connecting a central portion of a chamber with the central bore, fluid inlet and outlet ducts, a rotatable shaft journalled in the central bore and having valve means for connecting chamber ports with inlet ducts during intake strokes of their associated pistons and for connecting chamber ports with outlet ducts during discharge strokes of their associated pistons, the ends of the housing beyond which the shaft extends being provided with plane surfaces at right angles to the axis of the shaft, devices located adjacent the plane surfaces of the housing and so connected with the shaft as to limit longitudinal movement there-

of in relation to the housing and having provisions for causing the pairs of pistons in the chambers to reciprocate in opposite direction and to rotate while reciprocating in order to avoid scoring of the contacting surfaces of the pistons and chambers.

10. A fluid pump according to claim 9 in which each piston has a head having parallel plane surfaces oblique to the axis of the piston and in which one of the devices includes a structure integral with the shaft and the other is an integral unit detachably fixed to the shaft, each structure comprising a flange having a plane surface at right angles to the axis of the shaft and adapted to engage a plane at an end of the housing and having a plane surface oblique to the axis of the shaft for engaging the inner plane surfaces of the piston heads, each structure comprising a circular boss separated from the flange by a piston-head-receiving space and providing a journal for a wobble-washer, said boss being eccentric to the axis of the shaft and oblique thereto, and each structure comprising a wobble plate oblique to the axis of the shaft for engaging a

wobble-washer, and a wobble-washer mounted upon the eccentric boss of each structure and engageable with the outer surfaces of the piston heads, and with the wobble plate, and crank connections between the wobble washers and the piston heads adjacent thereto whereby, as the wobble-washers are caused to wobble and move eccentrically relative to the shaft, the pistons are caused to rotate in order to maintain their head-inner-surfaces in the planes of the adjacent oblique surfaces of the flanges and in order to maintain their head-outer-surfaces in the planes of the engaging surfaces of their adjacent wobble-washers, and whereby rotation of the pistons avoids scoring of the contacting surfaces of the pistons and chambers, the two motion transmitting devices being so positioned relative to the shaft that their plates and washers wobble in opposite directions and that the axes of their eccentric, wobble-washer-journaling bosses are on diametrically opposite sides of the shaft axis.
